UNITED STATES PATENT OFFICE

2,461,380

MATCH BOOK, VEST POCKET SIZE

Christine Hansen, Racine, Wis.

Application November 8, 1945, Serial No. 627,340

1 Claim. (Cl. 206—29)

1

My invention consists of an improvement in small match boxes or books of vest pocket size, which provides more convenience in handling and greater safety from accidental ignition than is found in the present type of small match boxes.

In order to obtain this security in use, this book is provided with a sliding door or front cover, which completely shields the matches in the pack, when a detached match is struck on the abrasive ignition surface which is bare on the front of the book.

This and other advantages of this vest pocket match book will be more readily understood by reference to the accompanying drawing and as set forth in the subjoined description.

Figure 1 represents a vertical section of the box or match book along line 1—1 of Figure 3.

Figure 2, a side elevation with the shield or sliding door removed.

Figure 3 is a front elevation or view of the book as seen from the left of Figure 1.

Figure 4 is a perspective view of said shield or door separated from the main cover.

In the figures, the same numerals represent the same details of the device and numeral 10 represents in general the main cover of card board or similar material with a plain back 11, which is folded across the bottom to provide an upwardly open channel 12, the upturned portion or edge 13 providing space on its outer surface for the usual abrasive layer upon which the matches are struck to be ignited.

The matches 14 are as usual bundled together in two rows, with their bottom ends 15 held together firmly by wiring or staples 16 in the channel 12, said staples running through the ends 15 as well as through the back and front portions 11, 13 of the cover, see Figures 1 and 2, in order to retain the match ends firmly and permanently together in the channel 12.

The cover 10 is at the top provided with a wide transverse space 17 for housing the free top ends or heads 18 of the matches. This space 17 is formed by bending the upper portion of the cover 11 back flatly, as at 19, at right angles, terminating with a double bent flap 20 to provide a narrow, transverse channel 21, the use of which will later be described.

It will be noted that the lowermost portion of the flap 20 barely covers the tips of the match heads 18, Figure 2. This is for the purpose of breaking off and pulling out a single match at a time when needed. In other words, the flap 20 need only be slightly raised or turned back for detaching a match from the bundle in the pack.

In order to fully protect the matches 14 in the main cover 10, a shield or sliding door 25 is provided which has a flat main portion of the same material as the main cover 10. This shield

2

has its upper end bent over in hook shape 27 adapted to fit snugly in the narrow top channel 21 of the main cover and has about the same width as the latter, while its height or length is of an extent to reach partway down in the bottom channel 21 of the cover 10. In this manner the entire front of the match comb is well protected as long as the shield remains in closed position in the cover 10.

When a match is needed the shield is pushed enough to one side to uncover a match while the flap 20 is lifted slightly to break off and detach a match from the pack. Then the shield is pushed back in place thus protecting all the other matches, while the one to be used is lit by striking its head along the abrasion surface at 13. No spark or flame can thus reach matches behind the upturned portion 13 of the cover and the shield 25.

It is to be understood that the invention as here disclosed is not limited to the details here described and shown but that the same may be varied without departing from the spirit of the invention as defined by the subjoined claim.

25 I claim:

In a safety match box of vest pocket size, a main cover having its bottom edge upturned to form an open channel and its top edge having a flap bent over to form a wide housing space for 30 match heads and the extremity of the flap bent inwardly in said space to provide an upwardly open narrow channel, a match comb with a plurality of matches enclosed in said cover having its solid bottom end rigidly secured in the upturned bottom channel of said cover and the heads projecting freely into said top housing space, said flap concealing only the tips of the match heads, and a shield having a flat straight body of about the same width as said cover and 35 a height greater than the distance between the opposing edges of said flap and said bottom channel, said shield being bent over at its top edge to form a hook portion adapted to hook over the edge of said narrow tip channel of the cover thereby to cover the entire front of the matches 40 and being adapted to slide sideways for uncoving them.

CHRISTINE HANSEN.
